Lawrence, Attorney

UNITED STATES PATENT OFFICE.

OTIS H. BURDETTE, OF ATLANTA, GEORGIA.

PENHOLDER.

Application filed March 28, 1922. Serial No. 547,437.

To all whom it may concern:

Be it known that I, OTIS H. BURDETTE, a citizen of the United States, residing at Atlanta, in the county of Fulton and State 5 of Georgia, have invented certain new and useful Improvements in Penholders, of which the following is a specification.

This invention relates to improvements in penholders.

10 The ordinary penholder presents the disadvantage that after it has been in use for some little time, the pen seat will become so fouled and clogged with dried ink as to render it difficult to properly fit a pen point into the seat. Or, if the pen point is allowed to remain in the seat of the holder for a considerable period of time and is not frequently cleaned, it and the seat will become corroded and great difficulty will be experienced in removing the pen point without damage to the seat. Therefore it is the primary object of the present invention to provide a penholder embodying a novel construction of seat for the pen point adapted 15 to firmly grip and support the point in a substantial and rigid manner and yet capable of yielding in a manner to provide for the most ready and convenient insertion of the pen point therein and the removal of the point therefrom.

Another object of the invention is to so construct the pen point gripping and holding means of the seat as to adapt the point to be sprung away from the wall of the 20 ferrule of the seat in the act of removal and therefore break apart the said elements in the event they have become corroded and mutually united by the corrosion.

In the accompanying drawings:

25 Figure 1 is a detail longitudinal sectional view through one form of penholder embodying the invention;

Figure 2 is a perspective view of the penholder with the ferrule removed to better 30 illustrate the form and arrangement of the component parts of the pen gripping and holding means;

Figure 3 is a view similar to Figure 1 illustrating a modification of the invention;

35 Figure 4 is a perspective view of the pen gripping member shown in Figure 3; and

Figure 5 is a plan view of the blank from which the gripping member is formed.

In the drawings and more particularly in 40 Figures 1 and 2, the staff of the penholder

is indicated by the numeral 1 and may be of wood or any other material suitable for the purpose and of any desired dimensions and contour. The staff is provided with a forward reduced end indicated by the numeral 2 onto which is fitted the pen point gripping and holding member of the invention indicated in general by the numeral 3. This member is preferably formed from sheet metal and comprises a tubular body 4 45 snugly fitted onto the reduced end 2 of the staff and provided at its forward end and at one side with a relatively rigid pen seat indicated by the numeral 5. This seat is in the nature of a finger constituting a forward extension of one side of the sleeve 4 and is transversely curved to the same form as the wall of the said sleeve except at its end where it is also longitudinally curved 50 as indicated by the numeral 6 so as to provide a rounded nose. A ferrule 7 is fitted onto the sleeve 4 of the member 3 and is thus supported upon the end of the staff 1, and this ferrule has its forward end extending a suitable distance beyond the end of the nose 6, and while the seating finger 5 for the greater portion of its length bears against the wall of the ferrule, it bends 55 away from the surface of said wall at its nose end 6 so that the butt end of a pen point fitted into the ferrule 7 may be readily engaged between the rounded nose of the seating finger and the wall of the ferrule, this end of the pen point being fitted or wedged between the said finger and ferrule 60 for a greater or less portion of its length and being thus afforded firm support at said end. The finger 5, it will be understood, is relatively rigid, being yieldable 65 only to an extent to permit of the wedging fit of the butt end of the pen point between its nose and the wall of the ferrule 7.

A pen point gripping finger 8 extends from the said forward end of the sleeve 4 at the side opposite the finger 5 and this gripping finger 8 comprises a shank portion 9 integrally connected with the said forward end of the sleeve 4 and constituting in effect a continuation of the said side of the sleeve. Beyond its shank portion 9 the finger is 70 curved upwardly in the general direction of the finger 5 as indicated by the numeral 10 to provide a bearing portion 11 which is preferably transversely and longitudinally 75 rounded and which lies forwardly beyond 80

and in spaced relation to the nose 6 of the finger 5, being designed to bear more or less firmly against the wall of the ferrule 7 at the forward end of the latter, when the pen point is not in place. When the pen point is fitted into the seat of the holder, its butt end will wedge between the finger 5 and the wall of the ferrule 7 and its intermediate portion will be engaged by the bearing portion 11 of the finger 8, the finger bearing against the inner side of the pen point shank and binding the same firmly against the wall of the ferrule 7. Thus the pen point will be firmly retained within the ferrule but it will be evident that when its removal is desired, this may be readily accomplished even if the parts have become corroded and united by the corrosion, inasmuch as the pen point may be sprung inwardly away from the wall of the ferrule 7 upon the nose 6 as a fulcrum and against the resiliency of the finger 8, as shown in dotted lines in Figure 1 of the drawings. Therefore by the seating and holding means embodying the invention in the form described, the pen point is adapted to be readily and conveniently fitted into the seat of the holder and equally as readily removed therefrom even if the parts are corroded.

In the form of the invention shown in Figures 3 and 4 of the drawings, the staff is indicated in general by the numeral 12 and is provided with a reduced forward end 13 which directly constitutes the relatively rigid seating member of the device, being provided at one side at its forward end with a relatively rigid extension or finger 14 having a rounded nose 15 corresponding to the nose 6. A ferrule 16 is fitted onto the reduced end 13 of the staff, and the pen point, when fitted into the holder, is adapted to be wedged between the wall of the ferrule and the said finger 14 and its nose 15 as shown in Figure 3 and in the same manner as the butt end of the pen point is wedged between

the finger 5 and ferrule 7 in the previously described form of the invention. In this form of the invention the resilient or yieldable seating finger is indicated by the numeral 17 and the same is preferably formed from a strip of resilient sheet metal and comprises a shank 18 which is fitted between the reduced end 13 of the staff and the wall of the ferrule 16 and is provided at its inner end with a spur 19 which bites into the side of the said reduced end of the staff. The shank 18 is provided with a forwardly-extending angularly disposed portion 20 which is yieldable in view of the resiliency of the material from which the finger is formed, and the end portion of this part 20 is overturned or rounded as at 21 to provide a bearing portion designed to bear firmly against the inner side of the wall of the ferrule 16 at the end of the latter.

Having thus described the invention what is claimed as new is:

A penholder comprising a staff having a reduced end portion, a ferrule fitted on the reduced end of the staff, a sleeve encircling said reduced end portion of the staff within the ferrule, the ferrule projecting beyond the end of said sleeve, a finger integral with and extending from the end of the sleeve beyond the reduced end portion of the staff and arranged to receive between it and the wall of the ferrule the butt end of a pen point to be held, the said finger having a downwardly and forwardly rounded nose, and a yieldable resilient pen seating finger integral with and extending from the end of the sleeve below the first-mentioned finger and housed within the ferrule and having its free end rounded longitudinally and transversely to coact with the wall of the ferrule at a point in advance of the extremity of the first-mentioned finger.

In testimony whereof I affix my signature.

OTIS H. BURDETTE. [L.S.]
